ADJUSTABLE SUPPORT FOR FINGER SURGERY

Maurice C. Smith, Redlands, Calif.

Application July 10, 1950, Serial No. 172,950

10 Claims. (Cl. 128—20)

1

This invention relates to surgical appliances and more particularly to a device adapted to position and support a finger of the human hand for surgical operation thereon.

Surgical incisions in the fingers are frequently delicate and complex operations, the performance of which may be materially aided by the presentation and maintenance of the area to be incised in a firm and convenient position for an extended period of time. It is, accordingly, an important object of my invention to provide a device which is adapted to elevate a finger in a suitable position for operation thereon and firmly support the digit in such position during the entire operative period, in order that it may be at all times most accessible to surgery, irrespective of any muscular activity of the patient.

It is another object of my invention to provide a device of this character in which the finger to be worked upon (hereinafter frequently termed the "affected finger" or the "subject finger") is isolated from the remaining fingers and thumb of the hand and separately presented in a convenient location for incision, the remaining or idle digits being restrained to prevent any interference with the operation, either voluntary or involuntary, or contamination of an open incision on the subject finger.

A further object is to provide in a device of this character an adjustable finger positioning platform which is pivoted to facilitate manipulation and variation of the angle of inclination of the finger resting thereon, thus enabling the surgeon to position and support the affected finger at the most favorable acclivity for the expeditious performance of the operation during all stages thereof, irrespective of the portion or part of said finger to be incised.

Another object is to provide a surgical device which may be employed for operating on either hand, and on either the upper or lower surface of an affected finger, with the hand itself resting either palm downward or upward on the device.

Still another object is the provision of a device of this character which does not require in its function the assistance or cooperation of the patient but may be employed while the patient is under general or local anesthesia to position and support the subject finger and facilitate the surgeon's operative procedure.

Still another object of the invention is to provide a surgical appliance for finger operations which may be easily sterilized as an entire unit and manipulated and adjusted during surgery

2

without danger of contamination to the operator.

In a large number of finger operations the surgeon's work is performed in the deep subcutaneous areas of the digit, necessitating the cutting and drawing back of skin or skin flaps adjacent the incised area in order to expose various inner regions of the finger to view. It is essential that this skin on either side of the incision be securely maintained in retraction during the course of the operation without injury thereto and it is a further object of my invention to provide, in a device of the aforementioned type, self-retaining skin retraction means to facilitate the convenient exposure of the subcutaneous area to be worked upon by the surgeon.

Another object of the invention is to provide spring-biased skin retractors which are adjustably secured to permit variation of the setting thereof, in order that skin flaps of varying sizes and in diverse locations on the finger may be firmly retracted under a suitable tension at all times and without injury to the skin which is so withdrawn.

Other advantages will be apparent from the following description of an exemplary embodiment, as illustrated by the drawing, in which:

Fig. 1 is a plan view of the device with a right hand and fingers, palm upward, shown in phantom in operative position;

Fig. 2 is a partly sectional side view of same;

Fig. 3 is a transverse partly sectional view taken as indicated by the broken line 3—3 of Fig. 1; and

Fig. 4 is an enlarged transverse view taken on the line 4—4 of Fig. 3 showing details of an individual skin retractor.

The surgical appliance, as shown in the drawing, includes a rectangular base member indicated generally at 11 preferably fabricated of metal, for ease of sterilization, and having a peripheral depending flange 12 supporting a base platform portion 13 in spaced relation from a table or similar support (not shown) in the operating room. Rigidly secured to the base platform 13 at a central portion thereof, by means of a plurality of bolts 14, is a double-ended finger restraining member 15, comprising a channel-shaped central portion 16 having integrally formed therewith laterally extending restraining bars 17 substantially parallel to the base platform 13 and in spaced relation therewith.

Adjacent the outer end of each of the finger restraining bars 17 there is mounted a skin re-

traction assembly 18 including a binding post 19, a coil spring 20 and a skin retractor 25. The binding post 19 is adapted to adjustably secure an extension 21 of the spring 20, which is retained in a binding post aperture 22 by means of a binding post screw 23 having a knurled head 23a. The opposite end of the spring 20 is looped through an aperture 24 of the skin retractor 25, which, as shown in detail in Fig. 4, has a plurality of truncated prongs 26 which may be curved inwardly to best retain the skin in retracted position without puncturing same.

Positioned transversely of the finger restraining member 15 and having a segment of its length lying within the channel-shaped central portion 16 thereof, is a three-bar-link finger positioning and supporting assembly 28. An inclined finger supporting platform 29, in the form of a relatively narrow metal strip, comprises the upper link. The lower end 30 of the platform 29 is hinged by means of a hinge 31 to a hinge butt 32 which in turn is secured to the base platform 13 by means of a pair of the bolts 14 which pass through the butt 32 as well as the central portion 16 of the finger restraining member 15. The upper end of the finger supporting platform 29 is similarly hinged by means of a hinge 33 to an intermediate bar 34 of the three-bar-link, such bar 34 having a spatulate outer end portion 35 which is positioned to form a binder link, indicated at 36, with a similarly spatulate outer end portion 38 of a lower bar 37. The lower bar 37 is in turn hinged at its inner end by a hinge 39 to a hinge butt 40 which is secured to the base platform 13 by means of bolts 41 as best shown in Fig. 2. The spatulate end portions 35 and 38 of the intermediate and lower bars 34 and 37 are adjustably secured together by means of a screw 42 and a wing nut 43. The intermediate and lower bars 34 and 37, respectively, together with the finger supporting platform 29 form the three-bar-link which is maintained in any desired position of elevational adjustment of means of the adjustable binder link 36.

In order to restrain the thumb against movement toward the affected finger, thumb loops 45 and 45a are adjustably affixed to the base platform 13 adjacent corners 46 and 46a thereof, respectively. Each such loop is biased toward its corner by means of a coil spring 47 which at one end engages the thumb loop and at the other is adjustably retained by a screw 48, having a knurled head 48a, in a binding post aperture 50 of a binding post 49 affixed to the base member 11 adjacent the corner thereof.

The device described may be employed with either hand positioned palm upward or downward, as may be required to best present to view the portion of the affected finger requiring surgery. In usage, the patient may be under general or local anesthesia. In either event, the affected hand is placed partially on the base platform 13 of the previously sterilized device, with the fingers extended substantially perpendicular to the finger restraining member 15 and with the tip of the subject finger resting on the lower end of the finger supporting platform 29. The latter may be initially set at a relatively low inclination as illustrated in the drawing.

The hand and fingers are then moved into position by a forward sliding of the hand which carries all the fingers, except the one on which the operation is to be performed, beneath the

finger depressing bars 17. Such movement will also bring the affected finger up on the finger supporting platform 29 where it is positioned with the tip at or adjacent the hinge 33. In the event the affected finger is the first or fourth, all the remaining fingers will be beneath one bar only of the finger restraining member; and in this connection it is to be noted that each of the individual finger restraining bars extends laterally a sufficient distance to overlie the width of any three adjacent fingers of a normal hand.

With the subject finger thus positioned on the finger supporting platform 29 and the remaining fingers disposed beneath one or more of the finger restraining bars 17, the inclination of the finger supporting platform may be suitably adjusted to best present the affected finger to the surgeon. Such adjustment may be easily accomplished by loosening the wing nut 43 and pushing backward at the binder link 36 to increase the inclination of the finger supporting platform 29 or conversely pulling forward to decrease same. Such push or pull may be transmitted by the operator through the wing nut 43 itself, so that the loosening and tightening of the binder link 36 and the forward or backward movement imparted may be easily effected in one adjustment operation to achieve the desired setting of the supporting platform, or may be accomplished by applying force vertically at hinge 33.

After the fingers are positioned in the manner described, a thumb loop 45 or 45a is slipped over the thumb. Two such thumb loops are provided in order that in either palm-up or palm-down position of the right or left hand, a thumb loop will be suitably located for such engagement. The thumb thus encircled by the thumb loop is urged toward the corner 46 or 46a, as the case may be, by means of respective spring 47, which may be adjusted after loosening of its binding post screw 48, to vary the tension on the loop as may be required in accommodating different size hands in varying positions.

Prior to the commencement of the operation the hand is thus positioned with all the fingers, except the one to be incised, underlying the finger depressing bars 17 where they are restrained from conscious or subconscious interfering movement toward the affected finger into the zone of operation. By the "zone of operation" or the "operative zone," I have reference to the centrally located area of the apparatus occupied by and adjacent to the finger supporting platform. Similarly, the thumb is restrained from movement toward the operative zone and biased toward a spread finger position. The affected finger is supported on the inclined platform in a position most suitable for the surgeon's work in the zone of operation.

In the event the operation performed on the finger, thus supported and isolated, requires the cutting of skin flaps to expose subcutaneous regions, such flaps may be conveniently drawn back and held out of the way by means of the skin retractor assemblies 18 of my device. Each individual inwardly inclined retractor 25 is designed to engage the skin without puncturing the same and to maintain it in a retracted position with a minimum outward pull thereon, during the major portion of the surgery, the spring 20 providing the required tension on the retractor. Such tension may be adjusted to accommodate skin flaps of varying dimensions or in different locations on the finger by loosening of the bind-

ing post screw 23 and moving the spring extension 24 to the left or right in the binding post aperture 22 so as to exert only sufficient tension by means of the spring to maintain retraction.

If, during the course of the operation, it becomes desirable to alter the inclination of the finger supporting platform 29 in order to expose to better view or more convenient working position additional portions of the affected finger, the wing nut 43 may be loosened and the inclination of the supporting platform then varied by forward or backward force exerted thereon as heretofore described.

Thus it will be seen that I have provided a surgical appliance for use in finger surgery which not only adjustably supports and positions the subject finger for maximum efficiency in operation thereon, but also restrains the idle digits and isolates the subject finger to prevent any interfering movement into the zone of operation. Moreover, I have provided conveniently adjustable self-retaining skin retraction means for use in connection with my device.

The embodiment of my invention herein described in specific detail for the purposes of disclosure and to illustrate an application of the principles involved will suggest to those skilled in the art various modifications and substitutions that do not depart from the underlying inventive concept and I do not desire to be limited to the specific illustration disclosed herein and do hereby reserve the right to all such modifications and substitutions that properly come within the scope of the following claims.

I claim as my invention:

1. In an appliance for finger surgery the combination of: finger supporting means for positioning a subject finger of the human hand in an elevated position relative to the remainder of the hand for surgery thereon; and a finger depressing bar adapted to limit the movement of the remaining fingers of the hand toward said subject finger.

2. A surgical appliance for use in finger operations including: a base member for supporting a hand thereon; finger supporting means disposed in an operative zone centrally located with respect to said base member and extending obliquely upwardly therefrom, said finger positioning means being adapted to support a subject finger of the hand in an upwardly inclined position relative to the remainder of the hand during surgery thereon; and finger restraining means for limiting movement of the remaining fingers of the hand toward said operative zone.

3. A surgical appliance for use in operations on an affected finger of the human hand including: a base member; a movable finger positioning platform pivotally secured to said base member and extending obliquely upwardly therefrom, said platform being adapted to support the affected finger in an elevated position during an operation thereon; finger restraining means for limiting movement of the remaining fingers of the hand toward the affected finger; and thumb restraining means for engagement with the thumb of the hand to limit movement of the thumb toward the affected finger.

4. A surgical appliance for use in operations on an affected finger of the human hand including: a base platform; a finger positioning assembly pivotally mounted on said base platform comprising a finger supporting platform adapted to support the affected finger during an operation

thereon and means for varying the inclination of said finger supporting platform; and a finger depressing bar for limiting movement of the remaining fingers of the hand toward the affected finger.

5. A surgical appliance for use in operations on an affected finger of the human hand including: a base member; a movable finger supporting platform adjustably secured to said base member and adapted to support the affected finger during an operation thereon; finger restraining means for limiting movement of the balance of the fingers of the hand toward the affected finger; and thumb restraining means to limit the movement of the thumb toward the affected finger, such means including a thumb engaging receptacle adjustably secured to said base member.

6. A surgical appliance for use in operations on an affected finger of the human hand including: a base member; a movable finger supporting platform pivotally mounted on said base member and adapted to support the affected finger during an operation thereon; adjustable skin retraction means for retaining the skin adjacent an incision in the affected finger in retracted position during surgery thereon; finger restraining means for limiting movement of the balance of the fingers of the hand toward the affected finger; and thumb restraining means for engagement with the thumb of the hand to limit movement of the thumb toward the affected finger.

7. A surgical appliance for use in operations on a finger of the human hand including: a base platform; a movable finger supporting platform pivotally mounted on said base platform and adapted to support said finger during an operation thereon; spring-biased skin retractors adjustably secured to said base member at opposite sides of said finger supporting platform; a finger depressing bar for limiting the movement of the balance of the fingers of the hand toward the finger on which the operation is performed; and a thumb engaging receptacle adjustably secured to said base platform adapted to limit the movement of the thumb toward the finger on which the operation is performed.

8. A surgical appliance for use in finger operations including: a base member; a movable finger supporting platform centrally disposed with respect to said base member and pivotally mounted thereon; a finger restraining member including a central channel portion receiving one end of said supporting platform and having integrally formed on both sides of said channel portion finger restraining bars extending transversely of said finger supporting platform and in spaced relation from said base member; a spring-biased skin retractor adjustably secured adjacent the outer end of each of said finger restraining bars; and a pair of spring-biased thumb engaging receptacles each adjustably secured to said base member adjacent a corner thereof.

9. A surgical appliance for use in operations on a subject finger of the human hand including: a base member; a finger positioning assembly pivotally mounted on said base member comprising a finger supporting platform adapted to support said finger in an inclined position during an operation thereon and binder link means for setting said finger supporting platform at any desired position of inclination; a finger restraining member including a central

channel portion adapted to receive a segment of said supporting platform and having integrally formed therewith a finger restraining bar extending laterally in spaced relation from said base member and adapted to overlie the remaining fingers of the hand; a self-retaining spring-biased skin retractor adjustably secured adjacent the outer end of said finger restraining bar adapted to retract the skin adjacent an incision in the subject finger toward the outer end of the finger restraining bar; and a thumb retractor for engagement with the thumb of the hand to bias said thumb toward a spread-finger position.

10. A surgical appliance for use in operating on a subject finger of the human hand including: a base member; an adjustable finger positioning assembly comprising a plurality of pivotally connected bars, one of said bars being adapted to support the subject finger in an elevated position for surgery thereon and another 15 of said bars being secured to said base member;

and finger restraining means comprising a finger depressing bar adapted to limit the movement of the remaining fingers of the hand toward the subject finger during surgery thereon.
